UNITED STATES PATENT OFFICE.

FELIX SABBATANI, OF CAIRO, EGYPT.

TROUSERS.

No. 902,688.

Specification of Letters Patent.

Patented Nov. 3, 1908.

Application filed November 21, 1905. Serial No. 288,386.

To all whom it may concern:

Be it known that I, FELIX SABBATANI, residing at Cairo, Egypt, have invented certain new and useful Improvements in Trouser, of which the following is a specification.

My invention relates to trousers and particularly to the back-strap thereof; and an object of my invention is to provide trousers from which the back-strap may be readily removed and which, therefore, may be readily washed and ironed without the annoyance and disadvantages arising from having the back-strap secured permanently in place upon the trousers.

The figure shows in side view trousers provided with my new removable back-strap.

The back-strap f is attached at one end to the button b and is formed at its other end with a buttonhole f' through which passes the head e' of a button mounted upon the tab e''. The latter carries a buckle e with which is adapted to be engaged the tab x. The button b is provided with the head b'' which passes through the buttonhole g.

Through buttonholes in the sides k of the front opening m of the trousers project the heads a of buttons.

The straps d are connected at one end to the suspender strap d² by the double-headed button c; and at its other end each strap d passes over a roller b³ mounted upon a button b the head b'' of which passes through a buttonhole in the waistband of the trousers.

I claim:

Trousers the rear part of which is formed with a buttonhole and provided with a tab, in combination with a buckle adapted to engage said tab; a button adapted to engage in said buttonhole and formed with an opening; and a back-strap attached at one end to said buckle and provided with a button, the other end of said back-strap passing through the opening in said button and being formed with a buttonhole for engaging the last-named button.

In testimony whereof I have affixed my signature in presence of two witnesses.

FELIX SABBATANI.
